MACHINE FOR ASSEMBLING SHOES

Richard Gould, Brooklyn, N. Y., assignor to Municipal Shoe Co., Inc., Brooklyn, N. Y., a corporation of New York

Application January 17, 1933, Serial No. 652,110

2 Claims. (Cl. 12—7)

This invention relates to the manufacture of pre-welted shoes and consists of a machine and the steps of the method for assembling pre-welted shoes.

5 The usual method of making pre-welted shoes is to first stitch a welt to a vamp. The vamp is then applied to the last, to the sole of which has been applied an insole. The vamp is then drawn over the last with the aid of hand tools and the vamp is tacked to the insole and last. A considerable number of tacks must be used to hold the vamp evenly in position. Prior to these operations the leather has been treated or "tempered" to render it pliable. After the vamp has 10 been tacked the partly assembled shoe must be allowed to stand for several hours until the leather sets. The tacks are then drawn and the outsole applied to the shoe.

The above-described method is unsatisfactory 20 in several respects. It is expensive by reason of the number of steps involved, particularly the steps of tacking and removing the tacks. Furthermore, a great deal of time is lost in waiting for the leather to set. When the welt is stitched to the vamp a running loop-stitch is ordinarily used. In the tacking operation, if a tack is inadvertently driven through the stitch, the stitch will be cut and will unravel, and the welt will come away from the vamp.

25 Therefore, the object of this invention is to provide a method of assembly to eliminate the steps of tacking and removing the tacks and the delay in applying the outsole.

A further object of the invention is to provide a 30 machine to be used in the assembly of pre-welted shoes to eliminate several hand operations.

A further object of the invention is to provide a machine to be used in the assembly of shoes so that the tacking of the vamp may be eliminated, thereby removing the danger of cutting the 35 stitching with a tack.

A further object of the invention is to provide a machine to force a pre-welted vamp over a last.

40 A further, and more specific, object of the invention is to provide a pair of co-operating forming members to completely surround a last and force a pre-welted vamp evenly over the last.

The invention consists of the combination, construction, arrangement of parts and the steps of the method, as herein illustrated, described and claimed.

45 In the accompanying drawing, forming part hereof, is illustrated one form of embodiment of the invention, in which drawing similar refer-

ence characters designate corresponding parts, and, in which:

Figure 1 is a side elevation partly broken away;

Figure 2 is a rear elevation showing the construction illustrated on the right-hand side of Figure 1;

Figure 3 is an enlarged fragmentary detail in vertical section showing the jaws of the machine in closed position; and,

Figure 4 is a plan view of the forming members or jaws.

Referring to the drawing 5 designates a base on which is carried an anvil 6 provided with a vertical horn 7. An extension 8 supports a pair of friction rollers 9 over which rollers is passed a wire loop 10. The wire loop 10 is connected to a pedal 11 for operation as hereinafter described.

Disposed on the horn 7 is a last 12 on which is disposed an upper or vamp 13. A welt 14 is stitched to the vamp 13 with the finished surfaces of the vamp 13 and the welt 14 in a face-to-face relation. On the sole portion of the last 12 is placed an insole 15 and a filler sole 16 adapted to receive an outsole 17 as hereinafter described. All of the parts above described are of common construction and are well known in the art.

A pair of plates 18 are secured in spaced relation by bolts 19 and are secured by bolts 20 to a sub-base 21 disposed on the base 5. A pair of complementary bell crank arms 22 are secured by pivots 23 between the plates 18 near the upper end thereof. A spring 24 is carried by hooks 25 disposed on the lower portion of the arms 22 to normally maintain the lower portion of the arms 22 close together and thus maintain the upper ends of the arms 22 separated.

Carried by the upper ends of the arms 22 are a pair of complementary plates 26. The plates 26 are secured to the arms 22 by studs 27. Each plate 26 is provided with a dowel 28 adapted to enter a recess 29 in the opposite plate to insure proper alignment of the plates 26 when they are brought together as hereinafter described. The center portion 30 of the plates 26 is cut away to provide an opening having the contour of a sole. The portions 31 of the plates 26 adjacent the cut-out portions 30 are reduced in thickness so as to provide a relatively thin but not sharp working edge.

50 The arms 22 are provided with rounded faces 32 on the lower part thereof, which faces 32 are disposed in the path of movement of a rounded upper end 33 of an actuating head 34 disposed between the plates 18. The head 34 is carried 55

by a guide block 35 which rides in a slot 36 in one plate 18. The guide block 35 carries an operating rod 37 which is connected to a second pedal 38 so that when the pedal 38 is depressed the rod 37, block 35 and head 34 will move upward. The upward movement of the head 34 will separate the lower part of the arms 22 and bring the upper part of the arms 22 with the plates 26 together.

In the assembly of the shoe the insole 15 which carries the filler sole 16 may be placed on the last 12 and may or may not be temporarily secured thereto with a tack. A vamp 13 with the welt 14 already stitched thereto is then placed on the last 12 and the last 12 is placed on the horn 7 of the anvil 6.

The wire loop 10 is placed around the vamp between the vamp 13 and the welt 14 and upon operation of the pedal 11 the wire 10 is tensioned and draws the toe portion of the vamp 13 over the last 12. If desired the use of the wire loop 10 may be eliminated and the toe portion drawn over in a preliminary manner by hand.

If the loop 10 is used, after the toe portion has been drawn over the last 12, the loop 10 is slackened and dropped and the pedal 28 is operated to bring the plates 26 together. The edges 31 of the plates 26 will engage the vamp 13 and the welt 14 adjacent the line of stitching which holds the vamp and the welt together. If desirable, the welt 14 may be turned away from the vamp 13 by hand so as to present a larger space between the vamp and the welt for the entry of the edges 31 of the plates 26. As the pedal 38 is moved further downward the edges 31 of the plates 26 will ride over the last 12 and force the vamp 13 and the welt 14 to the position shown in Figure 3. Since the plates 26 entirely surround the last 12 and the edges 31 are shaped to conform to the shape of the last, the vamp 13 will be forced over the last evenly at all points.

While the plates 26 are maintained in closed position the welt 14 is straightened out if this be necessary. If the welt 14 has been turned up by hand before the plates 26 were brought together it is necessary to again smooth out the welt 14 and the edges 31 of the plates 26 serve as an anvil for this purpose. If a tack has been used to secure the insole 15 and the filler sole 16 to the last 12 such tack is now removed since the vamp 13 and the plates 26 hold the insole 15 firmly in place.

When the welt 14 is smooth the outsole 17 is applied. The inner surface of the outsole 17 is coated with a suitable adhesive agent and is placed firmly against the welt 14 and the filler sole 16.

If a proper adhesive agent is used on the outsole 17 the plates 26 may be immediately opened by releasing the pedal 38 and the vamp 13 with the welt 14 will be maintained in proper position by the outsole 17. The shoe is now ready for the

stitching or any other desired finishing operation.

The time necessary to assemble a shoe with the use of the hereinbefore described machine is much less than the time necessary to assemble the shoe by hand. As will be readily seen the use of tacks to hold the vamp to the insole and last is eliminated so that the steps of applying the tacks and removing them is eliminated, together with the danger of a tack inadvertently cutting the stitching between the vamp and the welt.

When a shoe is assembled by the ordinary method the welt is rough and uneven by reason of being pulled over the last by hand tools, and the shoe must be subjected to a further machine operation to smooth out the welt. With the use of the machine described herein the welt is not roughened and it is therefore unnecessary to smooth out the welt again except to lay the welt over if it has been raised to permit the entry of the plates 26. If this be necessary, it is done at 20 the time the outsole is applied and does not require a separate operation.

The invention is not limited to the operation of the operating rod 37 and the wire 10 by their respective pedals. It is contemplated that the 25 moving parts may be motor-driven.

The invention is not limited to the use of two plates 26 since the object of the invention is to provide a plurality of plates 26 to entirely surround a last. For instance, a third plate 26 may 30 be used to operate on the toe portion of the vamp. With such construction the plates 26 illustrated would be reduced in length so as to operate only on the sides and back of the shoe. A third arm 22 would be provided to carry the third plate 26 35 and the curved portion 32 of the third arm 22 would be varied so that the third arm 22 carrying the toe plate 26 would operate slightly in advance of the side plates 26 in order to force the toe portion of the vamp over the last in advance of the 40 side portions of the vamp.

Having thus fully described the invention, what is claimed as new and desired to be secured by Letters Patent of the United States, is:

1. A pre-welt shaping machine comprising supporting means for a pre-welt shoe upper, a flexible device arranged to engage a curved end portion of the shoe upper at the welt, mechanism for operating said device, and substantially inflexible shaping members operative to engage and shape 45 the inwardly curved side portions of the shoe upper at the welt.

2. A pre-welt shaping machine comprising a support for a pre-welt shoe upper, a flexible shaping device having a curved portion for engaging 55 and shaping a curved end portion of the shoe upper at the welt, and plates having curved edges adapted to engage and shape the curved side portions of the shoe upper at the welt.
